UNITED STATES PATENT OFFICE.

JAMES H. BIGALOW, OF RAVENNA, OHIO, ASSIGNOR TO THE A. C. WILLIAMS COMPANY,
OF RAVENNA, OHIO, A CORPORATION OF OHIO.

DESIGN FOR A TOY BANK.

59,701.

Specification for Design.

Patented Nov. 22, 1921.

Application filed August 16, 1921. Serial No. 492,841. Term of patent 14 years.

To all whom it may concern:

Be it known that I, JAMES H. BIGALOW, a citizen of the United States, residing at 109 E. Highland, Ravenna, in the county of Portage and State of Ohio, have invented a new, original, and ornamental Design for Toy Banks, of which the following is a specification, reference being had to the accompanying drawings, forming part thereof.

In the drawings, Figure 1 is a front elevation, and Fig. 2 a side elevation of a toy bank, showing my new design.

I claim:

The ornamental design for a toy bank as shown.

JAMES H. BIGALOW.
